CLAMP

Robert R. Frederick, Morrisville, Pa., assignor to
 Sloane-Elbon Corporation, Trenton, N. J., a
 corporation of Delaware

Application January 21, 1937, Serial No. 121,534

6 Claims. (Cl. 24—248)

This invention relates to an improved clamp and particularly to a clamp for use in gripping and handling large, comparatively thin sheets of sheeted material, such as felt base floor covering, linoleum, rubber and the like.

The clamp is especially suitable for pulling sheets of printed felt base or linoleum into the heaters or drying racks. The clamps heretofore used required a relatively large space or opening 10 between the various drying racks in order that the clamp fastened to the sheet material could be pulled through the racks. A conservative estimate of the space between the rack levels would be approximately 3 or 4 inches. However, 15 with the clamp, which will be hereinafter described as my invention, the space between the rack levels can be reduced inasmuch as the thickness of the clamp is substantially less than that of previously used clamps. The over-all thickness of my clamp may be as small as 1 inch, and the results accomplished by the clamp will be 20 equally as satisfactory as heretofore obtained with other clamps. Thus through the use of my clamp, the number of racks in the heater can 25 be increased thereby increasing the heater capacity.

It is, therefore, among the objects of my invention to provide a clamp which is relatively thin and can be used in pulling sheet materials 30 into drying racks which are spaced less distance apart than the drying racks now found in heaters used in drying sheet materials.

Another object of my invention is to provide a clamp which is of simple and rugged construction 35 adapted to withstand the abuses to which clamps are ordinarily subjected to in pulling heavy sheet materials. The clamp is simple in construction in that it has relatively few moving parts and in being constructed substantially 40 throughout of metal and leather, the ruggedness of the clamp will be quite apparent.

Another object of my invention is to provide a clamp which takes and maintains a secure grip 45 on the sheet material being handled and at the same time will engage only a very narrow portion of the sheet material. The clamps previously used required relatively large gripping areas in order to acquire a firm grip or hold on the sheet 50 material, thereby causing considerable damage to the material. The clamp described as my invention engages a very narrow edge of the sheet material, approximately three-eighths of an inch, thus eliminating the necessity of re-processing 55 or scrapping of large quantities of the processed

sheet material which were previously damaged by the larger and wider clamps.

A further object of my invention is to provide a clamp which will engage the edge of the entire width of the sheet material thereby acquiring a more secure grip on the sheet than has heretofore been obtained with clamps that had spaced clamping elements. It is obvious that if a clamp should become loosened from the sheet as the material is being pulled into the drying racks, 10 considerable damage would result and the clamp described as my invention eliminates substantially all possibility of such an event occurring.

A further object is to provide a clamp which is relatively simple to operate and light in weight 15 thereby eliminating extra labor ordinarily expended in handling the more complicated and heavy clamps. Previously, the large and heavier clamps were cumbersome and bulky and imposed an unnecessary burden upon the men who handled the clamps. However, through the use of my clamp, this unnecessary labor and expenditure of energy is eliminated.

My invention possesses other objects and features of advantage, some of which, with the ones 25 indicated above, will be apparent as my invention will be discussed in detail. It is understood that I do not limit myself to the disclosure of species of my invention, as I may apply varying embodiments thereof within the scope of the claims. 30

Referring to the accompanying drawings:

Fig. 1 is a plan view of my clamp.

Fig. 2 is a fragmentary perspective of the end of the clamp.

Fig. 3 is a perspective of the handle used to 35 operate the clamp.

Fig. 4 is a sectional view of sheet material extending through the slots of the fixed tube and the rotatable circular element and into the groove of the core. 40

Fig. 5 is a perspective view of my clamp, and shows the sheet material extending into the clamp.

Fig. 6 is a side view of a modified inner tubing which can be used in place of the inner element 45 disclosed in Fig. 4.

In terms of broad discussion, the clamp embodying my invention comprises a pair of substantially concentric elements having a longitudinal slot and groove, respectively, extending 50 substantially throughout the respective lengths of the elements. The outer tube is fixed securely to a suitable holding means. The inner grooved element is adapted to rotate within the outer tube and any sheet material which is inserted through 55

the openings of the concentric elements will be clamped securely between the walls of the inner and the outer elements.

In greater detail and referring particularly to the drawings, the clamp embodying my invention comprises a pair of concentric tubings or cylinders 2 and 3 having slots extending longitudinally substantially through the length of the tubes. The slots are best illustrated in Fig. 4. The inner tube 3 has a rounded or tapered portion, as noted at 5, at one of the edge portions of the slot. The rounded or tapered portion is necessary to prevent a shearing action of the sheeted material 21, as the inner tube 3 is rotated within in tube 2. 10 15 20 25 30 35 40 45 50 55 60 65 70 75

A core 4 having a longitudinal groove 6 extending substantially throughout its length is fixed within the tube 3. The core may be made of wood, metal or any other suitable material adapted to withstand rough treatment, but which, at the same time, is comparatively light in weight so that the weight of the clamp is not unduly increased.

A substantially T-shaped metallic element or holder is secured to the outer tube 2, and flexible straps 8 are, in turn, fixed to the stem of the T-shaped element as illustrated in Figs. 1, 4 and 5. A harness 20 unites the straps 8 and is brought together at 16 to form a reinforced point for the insertion of the hook used in pulling the sheet material through the heaters. 20 25 30 35 40 45 50 55 60 65 70 75

Handles 10 are fastened at each end of tube 3 which enables the inner tube and core to be rotated to open and close the clamp. The handle, as shown in Fig. 5 is in a closed position and is held locked in place through the medium of a locking pin 19 which slides in groove 18 and is adapted to penetrate the opening 17 of the handle. A handle for the operation of the clamp is not necessary at each end since the clamp can readily be operated by one operator, but for convenience in operation, a handle is shown at both ends. In actual use, it is preferable to move the handles at each end of the clamp simultaneously which will relieve an unnecessary twisting or torque action upon the inner tube. In order to remove the clamp from the sheet, the operation can be handled very satisfactorily with one handle, after the locking pins at each handle have been released since, in releasing the clamp, it is merely a question of releasing the pressure previously exerted on the edge of the sheet.

A typical handle, especially suitable for use in operating the described clamp, is shown in Fig. 3, however, this handle is merely illustrative and is not to be construed as the only type handle adapted to the invention. The elements 13 and 14 are set screws which enable the handle to be loosened, fastened or adjusted in a very short time. In order to make rapid adjustments of the handle to keep the slotted openings of tubes 2 and 3 in proper alignment which is necessary to receive the sheet material, it has been found that roughened surfaces, as indicated at 11 and 12, are especially suitable for rapid and accurate adjustments. This feature is particularly important in cases where the clamp must be adjusted to compensate for different gauges of the processed sheet material, or when, for any other reason, there is need for a tighter or more secure gripping action upon the sheet. It is possible that the gripping action of the clamp may be decreased after being used for a period of time due primarily to normal wear and tear upon the various clamp elements, but the roughened surfaces make it possible that the original grip-

ping action may again be obtained by merely adjusting the handle. The roughened surfaces may be fine groovings, threads or equivalent markings, but it is understood that the invention is in no way limited by these features. 5 10 15 20 25 30 35 40 45 50 55 60 65 70 75

In operating the clamp, the slotted openings of the concentric tubes are brought into alignment as shown in Fig. 4. The handle 10 is shown in the open position in this figure. The sheet material 21, ordinarily supported on a table 22, is entered through the opening 9 of tube 2, then through the opening of tube 3 and finally into the groove 6 of element 4. The depth of the groove 6 will serve as the limiting means as to the amount of material inserted into the clamp and which will be subjected to the clamping action. The handle 10 is then pulled from the position indicated in Fig. 4 to the closed position as indicated in Fig. 5. As the handle 10 is pulled toward the closed position, the slotted tube 3 and core 4 are turned and the sheet material will be clamped between the inner walls of tube 2 and the walls of tube 3. Inasmuch as tube 3 has a rounded or tapered edge as indicated by the numeral 5, no shearing of the sheet material will occur. The action will tend to hold the sheet firmly and the grip will not be loosened except when the handle is brought back to the open position shown in Fig. 4. After the handle has been brought into the closed position shown in Fig. 5, the key 19 is slid forward through the opening 17 of the handle and the gripping action cannot be lessened until the key is moved back and the handle released. 30 35 40 45 50 55 60 65 70 75

A modified form of the inner tubing is shown in Fig. 6. The modified form eliminates the use of the central core 4. In the modified form the inner tube does not have a longitudinally extending slot as disclosed in tube 3, but has a longitudinally extending groove 24 extending substantially through the length of the tube 23. The modified form is merely substituted in place of the grooved circular element and can be used with equal adaptation as the combination slotted tube 3 and grooved core 4, and is, therefore, included within the scope of the present invention. 30 35 40 45 50 55 60 65 70 75

The sheet material is inserted through the slot of the outer tube, and thence to the bottom of the groove 24 of tube 23. The bottom of groove 24 will limit the amount of sheet material which can be inserted into the clamp. When the tube 23 is turned through the medium of the handles, the gripping action upon the sheet material will occur in the same manner as described above. 50 55 60 65 70 75

The metallic elements, as the tubings and the T-shaped element, are preferably made of any comparatively light weight metals so that the clamp will be relatively convenient to handle. This light weight feature is important since such clamps are being constantly handled in pulling sheet materials into and out of heaters; however, if the question of weight and strength is not essential, any material can be used. It should be understood that the drawings are merely illustrative and do not pretend to give exact proportions. Furthermore, the said drawings and description are illustrative of preferred constructions; however, it is clearly evident that the modifications may be further altered by one skilled in the art without departing from the spirit and scope of the invention. 60 65 70 75 80 85 90 95

I claim:

1. A clamp for gripping the edge of a sheet material which comprises a slotted tube securely fixed to a holder, a grooved circular element in-

cluding a slotted tube and a grooved core placed within said first-named slotted tube, and substantially concentric thereto, and means to move said grooved circular element with relation to the 5 fixed slotted tube.

2. A clamp for gripping the edge of a sheet material as defined in claim 1, in which the edge of the grooved circular element is rounded.

3. A clamp for gripping the edge of a sheet 10 material as defined in claim 1, in which the edge of the grooved circular element is tapered.

4. A clamp for gripping the edge of a sheet material which comprises a slotted metallic tube securely fixed to a holder, a grooved circular element including a slotted member and a grooved

core placed within the slotted tube and substantially concentric thereto, said slot of the tube and groove of the circular element being in alignment to receive the edge of a sheet material, means to move the grooved element to move the 5 slot and groove out of alignment to a closed position, thereby clamping the sheet material, and means to lock the clamp in the closed position.

5. A clamp for gripping the edge of a sheet material as defined in claim 4, in which the edge 10 of the grooved element is rounded.

6. A clamp for gripping the edge of a sheet material as defined in claim 4, in which the edge of the grooved element is tapered.

ROBERT R. FREDERICK. 15
